UNITED STATES PATENT OFFICE.

GEORGE V. WALLACE, OF WAKEFIELD, MASSACHUSETTS, ASSIGNOR TO BARCLAY, BROWN AND BIRD, INCORPORATED, OF BOSTON, MASSACHUSETTS, A CORPORATION OF MASSACHUSETTS.

STOCKING-PROTECTOR.

No. 874,880.

Specification of Letters Patent.

Patented Dec. 24, 1907.

Application filed July 10, 1907. Serial No. 383,006.

To all whom it may concern:

Be it known that I, GEORGE V. WALLACE, a citizen of the United States, residing at the town of Wakefield, in the county of Middlesex and State of Massachusetts, have invented a new and useful Stocking-Protector, of which the following is a specification.

The purpose of this invention is to provide a convenient and handy means, implement, 10 or device suitable for use to cover the stocking during the dressing or blacking of a person's shoe, boot, or other such like foot-covering and thereby to shield and protect the stocking against being defaced or soiled, 15 either as the dressing or blacking is being applied, or as it is being rubbed with a brush, cloth, or other means to produce the polish or other finish desired, it being of course understood that the blacking or dressing is done 20 when the foot-covering is on a person's foot.

For the purpose stated, this invention consists of a device or implement composed of a band of thin and flexible; as also, preferably, more or less resilient sheet material, 25 such as celluloid, hard vulcanized india rubber, metal, etc., which is in three distinct sections or parts, to wit,—a central and two end-parts,—and has an end of each of its end-parts overlapping and pivoted to the 30 central-part at one of its ends, and the other or opposite end of each end-part free and unconnected, and also has its said several parts of such relative lengths and widths that, when the device is applied for the purpose 35 stated at and within the shoe or boot at the upper edge thereof, the central-part will then cover the front and an adjacent portion of each of the opposite sides of the leg of the wearer, and the two end-parts, together, 40 or in coöperation, will cover the balance of the leg and overlap at the back thereof, and all otherwise as hereinafter fully described.

In the drawings, forming part of this specification, Figure 1, is a perspective view of a 45 low-cut shoe of any ordinary and well known kind, and showing in perspective the device or stocking-protector of this invention as inserted and placed therewithin. Fig. 2 is a face view of said stocking-protector removed 50 from the shoe of Fig. 1, with its said several parts distended for their full length.

In the drawings, A indicates the stocking-protector considered as one whole. This protector, in all of its parts or sections B, C and 55 D, is to be made of a thin and flexible sheet

material, such as celluloid, metal, hard vulcanized india rubber, leather, or cloth, etc., but, preferably, a sheet material is to be used which is also resilient, as for instance, celluloid, metal or hard vulcanized india rubber, 60 although this invention is not to be limited in this regard, it being intended to use any sheet material which will best serve the purpose of this invention.

B and D are the two end-sections or parts 65 and C is the central-section or part. The central-section C, at each, of its ends, and in each instance, is overlapped by an end of one of the end-sections B and D, as shown at E, and each of these so overlapping 70 ends—the other or opposite ends being free or disconnected—is secured to the portion of the central-part, which it overlaps, by a riveted or headed swivel-pin or pivot F, which passes through their combined thickness and 75 otherwise both pivots are so applied as to leave the end and central-sections free to be swung, with more or less freedom, as may be deemed desirable, on each other, all so that the end and central-sections can be adjusted 80 or placed either in a continuous coincident line or direction, or in lines or directions, more or less at an acute or an obtuse angle to each other, according as may be found best for the device to serve the purpose of its use 85 as herein before stated.

J and K are the free ends of the end-parts B and D, respectively, and, preferably, they are rounding as also are their attached and pivoted ends. Further they are tapered 90 from their said attached ends to their said free ends. The central-part C, preferably, is also rounded off, at its opposite ends, and between its two ends, preferably, its upper and lower edges M and N, respectively, from end 95 to end, are concave, see Fig. 2.

The shape of the end and central-parts B, D and C, as described and shown, secure better conformity of the stocking-protector to the curvatures of the foot and leg of the person when inserted in the shoe (see Fig. 1) to protect the stocking of the person from being defaced or soiled as the shoe is being blacked, polished, or otherwise treated to surface it as may be desired.

In using the protector described the central-part C, covers and protects the front and a portion of each side of the leg adjacent thereto and the balance of the leg is covered and protected by the two end-parts B and D 110

which, by their free ends, overlap at the back of the leg.

It is obvious that the protector described is capable of use for varying sizes of foot 5 wear but it is desirable in all cases of its use that the free ends of the end-parts should overlap as stated.

It will be observed that it is most preferable to make the protector described of a material which can be readily washed or otherwise cleansed, from time to time, without injury thereto, as for instance, of celluloid or 10 hard vulcanized india rubber.

Having thus described my invention; what 15 I claim and desire to secure by Letters Patent is,

1. As a new article of manufacture, a stocking-protector, consisting of two end-parts or sections and a central-part or section, severally of flexible sheet material and having each of the two end-parts, at one end, pivoted 20 to one end of the central-part, and the opposite end of each free and unconnected so as

to overlap each other, substantially as described, and for the use specified.

25

2. As a new article of manufacture, a stocking-protector, consisting of two end-parts or sections, and a central-part or section, severally of flexible sheet material and having each of the two end-parts, at one end, pivoted 30 to one end of the central-part, and the opposite ends of each free and unconnected, and also having each of said end-parts tapered from their pivoted-end to their free end, and rounded off at their opposite ends, 35 and the said central part rounded off at its opposite ends and therebetween concaving along each of its edges.

35

In witness whereof, I have hereunto set my hand in the presence of two subscribing witnesses.

40

GEORGE V. WALLACE.
